UNITED STATES PATENT OFFICE.

JOHN A. TOOMEY, OF CHICAGO, ILLINOIS.

CAR-STAKE AND ATTACHING MEANS THEREFOR.

No. 884,778.

Specification of Letters Patent.

Patented April 14, 1908.

Application filed May 20, 1907. Serial No. 374,683.

To all whom it may concern:

Be it known that I, JOHN A. TOOMEY, a citizen of the United States, and a resident of the city of Chicago, in the county of Cook and State of Illinois, have invented certain new and useful Improvements in Car-Stakes and Attaching Means Therefor; and I do hereby declare that the following is a full, clear, and exact description of the same, reference being had to the accompanying drawings, and to letters of reference marked thereon, which form a part of this specification.

This invention relates to improvements in car stakes and attaching means therefor.

It is an object of this invention to provide a car stake and attaching mechanism of few parts, positive in operation and in which the stake is adapted to lock itself in vertical position.

It is a very important object of this invention to provide a device of the class specified in which the attaching mechanism has interlocking parts covering maximum area which prevents the stake from being sprung away from the car sill by outward pressure of the load and also a device in which the pressure exerted at said interlocking parts is equally distributed over very large area thus affording great rigidity with light weight.

It is a further object of this invention to provide a foldable stake slidable relatively of the car and attaching mechanism together with means for positively locking the stake from movement when turned to a horizontal position and which positively prevent the stake at all times from turning below the horizontal position and means for locking adjacent stakes together to prevent longitudinal movement thereof when in horizontal position.

It is also an object of this invention to provide a strong rotatable housing for the stake and through which the same extends and means operatively connected thereto for rotating the housing and stake in effecting the adjustment.

It is finally an object of this invention to provide a device of the class specified very simple in construction, easy to operate and attach, which is positively secured in its adjusted positions and so firmly secured in operative position as to withstand terrific stress without breakage of parts or springing away from the car sill.

The invention relates to the matters hereinafter described and more fully pointed out and defined in the appended claims:

On the drawings: Figure 1 is a fragmentary side elevation of a car sill with devices embodying my invention attached thereto. Fig. 2 is an enlarged vertical section taken through the housing and sill with the stake in horizontal position. Fig. 3 is a rear elevation of a device embodying my invention with the stake in vertical adjustment. Fig. 4 is a similar view to Fig. 3 with the stake in horizontal adjustment. Fig. 5 is an enlarged front elevation of a device embodying my invention with the stake in vertical position. Fig. 6 is a section taken on line 6—6 of Fig. 5. Fig. 7 is an enlarged sectional detail of the means for locking the stakes together when horizontally disposed. Fig. 8 is an enlarged top plan view of the locked stakes.

As shown in said drawings: A indicates the side sill of a car with parts broken away to which is rigidly secured the sill of attaching plate B provided with a downwardly tapering portion B' which may extend below the sill. Said plate affords a broad bearing surface on the sill and is provided with apertures suitably disposed to receive the bolts b any desired number of which may be used to rigidly secure the same to the sill. Said plate is provided with a large central circular aperture and extending around the inner periphery of the plate and integral therewith is an outwardly tapering flange b' having an inwardly directed rim or flange b² as shown in Figs. 2 and 6 which as shown is parallel the side sill. Ribs b³—b⁴ are provided on opposite sides of said plate B, and webs b⁵—b⁶ integrally connect the same and said tapered flange b' as shown in Fig. 6 thus affording great strength. Integral with the tapered lower portion of said plate and extending outwardly therefrom are side and bottom walls b⁷—b⁸ and as shown ribs b⁹ integral with the plate and side walls firmly brace the same. A partition b¹⁰ integrally connects the side and bottom walls and the lower edge of the rim or flange b² affording a front stake pocket and a rear pocket for the lock as shown in Fig. 2. Said wall as shown in Fig. 2 curves slightly outwardly and downwardly for the purpose of throwing the bottom of the stake outwardly not only to afford a tight fit, but to incline the top somewhat inwardly. The

conical or tapered flange b' , is provided in its bottom with a notch b^{11} which opens into the rear pocket and a curved lip b^{12} integral with said flange extends into said rear pocket.

5 A rotatable stake pocket C is provided which as shown comprises a front wall c integrally connected with the sides of which are walls c' shaped to permit of maximum size for insertion through the central aperture in 10 the attaching or sill plate from the rear before engaged to the sill. Integral with the side walls of said housing at the rear edges thereof are approximately semi-circular plates c^2-c^3 having a diametrical space between the same. Integral brace bars c^4-c^5 bridge said space. The circumference of the circular rear wall of the stake pocket thus formed is greater than that of the aperture through the attaching plate B and in consequence 15 the edge of said plate engages behind the flange b^2 rotatively engaging itself and said stake pocket in place. A lever D extends through oppositely disposed notches in said side walls c' and is slidably in the diametrical slot before described and at its inner end d is forked to engage the rim or flange b^2 and near the opposite end of said lever has a shoulder d' which engages within the rim on the opposite side from the fork. Said lever 20 as shown is provided with a notch on its outer side of greater length than width of the stake which permits movement thereof without binding against the stake and the outer extremity of said lever is provided with a handle 25 d^2 for manual actuation.

The stake E employed is an ordinary I-beam of suitable size or may be of wood or any desired material, which is provided with a stop e secured thereon below the rotatable 40 pocket to prevent withdrawal of the same. A stop e' is provided on the opposite side of the rotatable pocket which at all times limits the distance the stake may slide through the said pocket.

45 For the purpose of locking the outer end of each stake to the adjacent stake when in horizontal position a transverse rib e^2 which may be integral with the stop e' is positioned a suitable distance above said stop e' and fits 50 between the flanges of the stake. Said rib is provided with an outwardly directed projection or pin e^3 which engages in an aperture in the outer end of the web of the adjacent stake when in horizontal position locking the stakes 55 together.

The operation is as follows: The housing is inserted through the aperture in the sill plate B from the rear until the plates c^2-c^3 bear against the rim or flange b^2 . The sill plate is 60 then bolted at the desired place. The lever D is inserted through the apertures with the forked end engaging the rim or flange b^2 on one side and the opposed shoulder on said lever fits within the rim on the opposite side. 65 The stake is now dropped in position and the

lever is locked from removal except by removing the stake. The stake fits in the notch in said lever as shown in Fig. 6. To turn the stake to horizontal position it must be lifted to clear the stationary pocket in the sill plate and the lever is then actuated, turning the rotatable pocket, and consequently the stake which can now slide in said rotatable pocket until the stake is in horizontal position when the forked end of the lever is above the notch in the flange b' and if released drops by gravity and the forks project beyond the rim b^2 one into the rear pocket. The stake is now locked from swinging, unless the lever is first raised when of course the stake may be returned to normal or vertical position when the stake drops by gravity, its lower end entering the stationary pocket and is secured snugly with its top inclined inwardly by means of the curved portion of the partition b^{10} . As the stake reaches the horizontal position the projection or pin e^3 on the stake extend through an aperture in the adjacent stake and inasmuch as the stakes are held from swinging said pins hold the same from longitudinal movement thereby preventing any relative movement of the stakes. A very great advantage obtained by this construction is the great strength and solidity and perfect adjustability of the construction, 95 which can withstand the tremendous outward pressure from the load without springing the stake out of operative position or affecting its operation.

High efficiency with extreme simplicity is secured and very few parts are employed. The stake can never be a source of danger as it cannot jar loose and touch the ground being rigidly and securely held in either adjustment. The use of the wide sill plate firmly 100 attached to the sill insures great strength and the equal distribution of pressure.

Many details of construction may be varied without departing from the principles of this invention and I therefore do not intend 105 to limit this application otherwise than necessitated by the prior art.

I claim as my invention:

1. A car stake and means for attaching the same having interlocking parts distributing 115 outward pressure thereagainst over a large area and a rigid pocket secured to the car adapted to receive the end of the stake when in vertical position and to lock the stake in said position.

2. A car stake slidably relatively of the car and adjustable to vertical and horizontal position, attaching means therefor resisting outward pressure thereagainst at points around the stake, a rigid pocket secured to 125 the car into which the lower end of the stake engages in vertical position and means rigidly secured to each stake for locking the outer end of an adjacent stake thereto in horizontal position.

3. A stake adjustable to a vertical and a horizontal position and means locking adjacent stakes together when in horizontal adjustment.
- 5 4. In a device of the class described the combination with a stake of attaching means therefor having interlocking parts affording great rigidity against outward pressure on the stake and means for inclining the stake 10 inwardly in vertical position.
- 5 4. In a device of the class described the combination with a vertically and horizontally adjustable stake of attaching means therefor part of which is rotatable, adapted 15 to interlock with another part and acting equally against pressure exerted on the stake for any adjustment of the stake, means for engaging the stake to lock the same in vertical adjustment and means for adjusting the 20 outer end of the stake inwardly in said adjustment.
- 5 6. In a device of the class described the combination with a car stake, of a plate having a pocket integral therewith, a rotatable 25 housing adapted to receive the stake and through which the stake is adapted to slide and circular interlocking parts on the housing and plate.
- 5 7. In a device of the class described the 30 combination with a car stake adapted for adjustment to a horizontal and vertical position of an attaching plate therefor having an aperture therethrough, a notched flange around the aperture, a housing adapted to receive the stake, means integral with the 35 housing adapted to lock behind the flange to firmly secure the housing in position and a gravity acting lever adapted to engage in the notch in the flange to lock the stake in horizontal 40 position.
- 5 8. In a device of the class described the combination with a car stake of a sill or attaching plate having a central aperture therein, a housing adapted to be inserted through 45 said aperture from the rear, plates integral with the housing, means integral with said sill plate adapted to coact with the plates on the housing to prevent the housing being sprung outwardly by pressure exerted on the 50 stake, a pocket integral with the sill plate into which the end of the stake engages and means for inclining the stake inwardly.
- 5 9. In a device of the class described the combination with a housing of a stake there- 55 for, an attaching plate having a pocket integral therewith to receive one end of the stake, segment plates rigidly secured to the housing and a flange integral with the attaching plate behind which the segment plates are 60 firmly locked.
- 5 10. In a device of the class described the combination with a stake of a housing or eas- 65 ing therefor, an attaching plate provided with an aperture therethrough, a flange around the aperture and means extending
- through slots in said housing adapted to engage the flange and by means of which the stake is turned to horizontal position.
11. A device of the class described comprising a stationary pocket, a pocket rotatable above the same, a stake slidable through the rotatable pocket adapted to extend into the stationary pocket to lock itself in vertical position and a reciprocating lever for locking the stake in horizontal position. 70
12. In a device of the class described the combination with a stake of a movable housing therefor, a stake slidable in the housing, stops rigidly secured to the stake above and below the housing and a lever for turning the 80 housing and stake to horizontal position.
13. In a device of the class described the combination with a stake slidable relatively of the car and a lever for turning the stake to horizontal position. 85
14. A device of the class described embracing an attaching plate, an aperture therein, a rotatable pocket adapted to be inserted therethrough from the rear, interlocking flanges on said plate and pocket, and a rigid pocket below the rotatable pocket to receive the stake therein. 90
15. In a device of the class described the combination with a stake of means rotatably attaching the same to the desired object and a lever for turning the stake to horizontal 95 and vertical adjustments.
16. In a device of the class described the combination with a sill plate of an outwardly directed tapering flange integral therewith having an inwardly directed locking rim or flange, a housing, means integral therewith adapted to engage behind the rim to firmly secure the housing in operative position for any adjustment of the stake and a lever extending transversely through the housing engaging the rim at one end adapted for manual actuation in adjusting the stake. 100
17. A car stake attaching device embracing mutually interlocking parts one of which is rotatable and through which the stake slides and a rigid pocket adapted to receive the end of the stake. 110
18. In a device of the class described the combination with a broad attaching plate having a pocket integral therewith, a housing pivoted to rotate over the face of said plate, a stake therein adapted at its lower end to seat in said pocket and lock itself in vertical adjustment, coacting parts on the housing and attaching plate securing the housing in operative position and a lever for rotating the housing and stake for its various adjustments. 115
19. In a device of the class described the combination with a stake of a housing or cas- 120 ing therefor, a plate adapted for engagement to the sill, a notched flange integral therewith having a locking rim, segment plates secured to the housing adapted to engage behind the rim, a lever extending through the 125
- 65

housing having a forked end to engage the rim adapted for actuation to rotate the stake to horizontal position, said forked end of said lever adapted to extend through the notch in 5 said flange to lock the stake in horizontal adjustment.

20. A device of the class described embracing interlocking parts one of which affords a rotatable pocket and the other a rigid 10 pocket, one end of said stake adapted to extend through the rotatable pocket into the rigid pocket.

21. In a device of the class described the combination with a casing or housing of a sill 15 plate having a circular flange and rim, segment plates secured to the housing to lock against the rim, a lever extending through the housing between said plates and engaging the rim of the sill plate, a stake for said housing 20 adapted to secure the lever in position and to prevent removal thereof, said lever adapted to turn the stake to horizontal position and to lock the same in said adjustment.

22. A car stake pocket embracing a fixed 25 part, a rotatable part protruding therethrough, a stake engaged by the rotatable part and adjustable to a vertical and horizontal position, and a flange on each part, one of which locks against the other, said 30 stake adapted to slide a predetermined distance through the rotatable part when being adjusted.

23. In a device of the class described the combination with an attaching plate having 35 outwardly directed side and bottom walls near the lower part thereof, of a housing rotatable over the face thereof, a notched flange integral with the housing having a circular rim or flange integral therewith, a lever 40 extending transversely through notches in the housing having one end forked to engage within the rim and a shoulder provided near the opposite end to engage within the rim, a stake adapted to secure said lever in position, 45 a partition connecting the side walls dividing the same into a stake pocket and a rear pocket, and an outwardly projecting handle on said lever adapted for manual actuation for rotating the housing in effecting the adjustment of said stake, said forked lever 50 adapted to drop by gravity through the notch in the flange and engage the partition to lock the stakes in horizontal position.

24. In a device of the class described the 55 combination with a stake slidable relatively of the car and adjustable to a vertical and a horizontal position of means preventing the stake from contacting the ground and a fitting on each stake intermediate its ends 60 adapted to engage in an aperture near the extremity of an adjacent stake to prevent longitudinal movement thereof in horizontal position.

25. A pocket for a retaining stake embrac-

ing a fixed part and a rotatable part interlocking therewith and affording a pocket. 65

26. In a device of the class described the combination with a rotatable housing of an adjustable stake therefor adapted to lock itself by gravity in vertical adjustment and a 70 lever for rotating the housing in effecting the adjustment of the stake and adapted to lock the stake in horizontal position.

27. In a stake attaching device a rigid 75 pocket and a rotatable pocket adapted to register therewith and through which the stake slides to engage at one end in the rigid pocket.

28. A stake attaching device embracing a rotatable pocket adapted to slidably receive 80 a stake and a rigid pocket adapted to receive one end of said stake therein and lock the same from swinging movement.

29. A stake attaching device embracing a rigid pocket, a rotatable pocket, interfitting 85 concentric flanges on the pockets and means extending through the rotatable pocket and engaging the flange on the rigid pocket for turning said rotatable pocket.

30. A stake attaching mechanism comprising 90 a rotatable pocket, through which the stake is adapted to slide, and adjustable to horizontal and vertical position, a rigid pocket adapted to receive the lower end of the stake and a part integral with the rigid 95 pocket for locking the rotatable pocket from displacement.

31. In a device of the class described the combination with a sill plate of a pocket integral therewith, a rotatable pocket secured 100 in position by the sill plate and a stake adapted to slide through the rotatable pocket and adjustable to a vertical and horizontal position.

32. In a device of the class described the 105 combination with a sill plate of a rigid pocket secured thereto, a pocket rotatable above the rigid pocket adapted to register therewith in vertical position and a stake slidable in the rotatable pocket adjustable to a horizontal 110 and a vertical position and engaging in the rigid pocket in vertical position.

33. A stake device embracing a rotatable and a rigid pocket, interlocking parts thereon and means in one of the pockets for inclining 115 the stake inwardly.

34. A stake attaching device embracing a rigid pocket, a pocket rotatable above the same, a stake in the rotatable pocket adjustable to vertical and horizontal position and 120 adapted to engage the rigid pocket and means secured to the stake for engaging the adjacent stake in horizontal position to prevent relative movement thereof.

35. In a device of the class described the 125 combination with a sill plate, a flange integral therewith, an inwardly directed rim integral with the flange, a rotatable pocket

adapted to extend through the rim, a flange integral therewith for locking against the rim and means for engaging the rim at one end for turning the pocket and locking the same in horizontal position.

36. In a device of the class described a sill plate provided with an aperture and having a tapering outwardly directed flange, an inwardly directed rim integral with said flange, a pocket adapted to be inserted through the aperture in the sill plate, plates rigidly se-

cured thereto adapted to lock against the rim and means adapted to rotate the pocket and lock the same in horizontal position.

In testimony whereof I have hereunto subscribed my name in the presence of two subscribing witnesses.

JOHN A. TOOMEY.
